GALVANOMETER

Samuel S. Leotta, Hatboro, Pa., assignor to Minneapolis-Honeywell Regulator Company, Minneapolis, Minn., a corporation of Delaware

Application October 12, 1949, Serial No. 5,440

Term of patent 14 years

(Cl. D52—1)

To all whom it may concern:

Be it known that I, Samuel S. Leotta, a citizen of the United States and resident of Hatboro, in the county of Montgomery and State of Pennsylvania, have invented a new, original, and ornamental Design for a Galvanometer, of which the following is a specification, reference being had to the accompanying drawing, forming part thereof.

Fig. 1 is front view in perspective of a galvanometer, showing my new design.

Fig. 2 is a side elevation as viewed from the left.

Fig. 3 is a plan view as seen from above.

I claim:

The ornamental design for a galvanometer, substantially as shown.

SAMUEL S. LEOTTA.
